BROILER DRAWER

Lewis Moore, Joliet, Ill., assignor to The Moore Corporation, Joliet, Ill., a corporation of Delaware

Application May 5, 1934, Serial No. 724,040

8 Claims. (Cl. 126—340)

This invention relates to stove construction generally and more particularly to improvements in broiler drawers for gas or other fuel stoves.

A principal object of the invention is the provision of a drawer structure for broilers which will facilitate the positioning of the broiler pan at selectively determined distances from the broiler heating medium.

An important object of the invention is the provision, in a broiler drawer, of pan supports which are automatically movable to a position in which the pan may be placed in the drawer from above at different selected heights from the bottom of the drawer, and may be connected, after having been thus positioned, with a fixed wall of the drawer.

A further object of the invention is the provision of a broiler drawer in which the rear supporting wall for the pan is mounted in the drawer in such manner that upon removal of the pan from the drawer the wall assumes a tilting position to increase the horizontal distance between the holding means on said wall and holding means on a fixed wall of the drawer, whereby the broiler pan may be lowered into the space between the two walls and may first be attached to the movable wall and then to the fixed wall.

A further important object of the invention is the provision of a broiler drawer wherein the adjustment of the pan to different heights in the drawer may be carried out without encumbering the interior of the drawer with pan adjusting mechanism.

Numerous other objects and advantages of the invention will be apparent as it is better understood from the following description, which, when taken in connection with the accompanying drawing, discloses a preferred embodiment thereof.

On the drawing,

Figure 1 is a longitudinal vertical section through a broiler compartment of the stove;

Fig. 2 is a vertical transverse section through this compartment; and

Fig. 3 is a fragmentary section on a larger scale, showing the supporting walls of the pan.

Referring to the drawing, reference character 1 indicates a broiler compartment of usual construction, in a gas or other fuel burning stove or range, within which is a drawer 2 removably located. This drawer is supported for sliding movement on rails 3 secured to the lateral walls of the compartment 1, and comprises a front wall 4 and bottom rail members 5 which are fixedly

secured to the front wall and which are or may be connected at the rear by an angle brace 6 to form a relatively rigid frame.

To facilitate the insertion or removal of the drawer in respect of the compartment 1, the rails 5 of the drawer have rollers 8 adapted to travel on the rails 3 of the compartment. The rails 3 fixedly mounted on the walls of the compartment, may be provided with additional rollers 9 on which the framework of the drawer 10 rests.

The front wall 4, which is fixedly secured to the frame by plates 10, is provided on its inner face with a plurality of brackets 11 vertically spaced from each other and adapted to serve as supports for the front flange 12 of a broiler pan 13. The pan 13 also is provided with a rear flange 14, and this rear flange may be secured to any one of several brackets 15 rigidly secured to the rear wall 16 of the drawer.

It will be obvious that it would be extremely difficult if not impossible to position the pan within this drawer by supporting it on any of the brackets 11 and 15 except the top pair. The spacing between the supporting brackets would have to be materially increased beyond the length of the pan 13 if it were desired to place the pan on the second or lowermost set of brackets of the front wall and rear wall.

For the purpose of permitting this insertion through elongating the spacing between the companion brackets of the front and rear wall, the rear wall 16 is mounted in the drawer in such manner that under normal conditions this rear wall will assume a position in which the supports mounted thereon are spaced from the corresponding supports on the front wall a distance greater than the length of the pan 13, whereby the pan may be lowered from the top onto the pertaining supporting brackets and may then be properly retained in the desired position.

To accomplish this, the rear wall 16 is provided, as shown in Fig. 3, with brackets 17 near its lower end, and these brackets are pivotally secured to the framework of the drawer at 18 at a point forward of the plane of the rear wall. It will be obvious, therefore, that the center of gravity of this structure comprising the rear wall 16 and the brackets 17 will be to the rear and above the pivotal point of support. Owing to this relation of the pivotal support to the center of gravity of this rear wall assembly, the latter has a tendency to assume a tilting position or to swing about the pins 18 to the left (Fig. 3) that is in the direction in which the center of

- gravity of the structure lies with reference to the pivotal support 18. The assembly also has its center of gravity at a considerable distance above the pivotal support, so that the assembly 5 may be described as being normally in unstable equilibrium. It has a tendency to assume stable equilibrium, and this tendency causes the movable wall to assume the tilting position, as shown in Fig. 3, and it would obviously swing beyond 10 said position if it were not for the portion 19 of the transverse member 6 of the framework of the drawer structure. This portion acts as a stop to limit the tilting movement of the rear wall assembly.
- 15 Upon removal of the pan 13 from the space between the front and rear walls, it might be possible to impart to the rear wall a swinging movement to the right (Fig. 3), and this movement also is limited by the engagement of the 20 lower portion of the rear wall assembly with the portion 19 and also by the engagement of a flange 20 of the wall with a portion 21 of the brace 6 which also constitutes a stop for the structure.
- 25 It will be apparent, therefore, that upon removal of the pan from operative position in the drawer, the rear wall will automatically assume the position shown in Fig. 3, in which position the spacing between the pan supporting brackets 30 of the front and rear walls is greater than the length of the pan, thereby permitting the pan to be positioned selectively in any of the brackets of the structure. Owing to the facility of movement of the rear wall assembly, the rear flange 35 of the pan 13 is first hooked into the selected bracket of the rear wall, and then the front hook is positioned on the respective front bracket by which movement the entire rear wall automatically is placed in upright position and is retained in this position owing to the insertion of 40 the rigid pan between front and rear wall and also, owing to the pivotal support of the rear wall and the engagement of the flange 20 thereof with the stop 21.
- 45 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.
- I claim:
- 55 1. A broiler drawer, comprising a frame, an end wall fixedly supported thereon, and an opposite end wall pivotally supported on said frame, the pivotal support of said end wall being disposed below the center of gravity of the wall, and 60 pan supporting brackets on each of said walls.
2. A broiler drawer, comprising a frame, a

front end wall fixedly secured to said frame, a rear end wall pivotally supported on said frame, the pivotal support of said rear end wall being located below the center of gravity of said wall, and pan supporting brackets mounted on both of said end walls at different spacings from the frame.

3. A broiler drawer, comprising a frame, an end wall fixedly mounted on the frame, another end wall pivotally supported by said frame, the pivotal support being disposed below and in front of the center of gravity of the wall, whereby said pivotally supported wall automatically slants away from said fixed wall, and pan supporting brackets mounted on said walls.

4. A broiler drawer, comprising a frame, end walls supported by said frame, one at least of said end walls being pivotally supported on the frame with the pivotal support located below the center of gravity of said wall, and pan support- 20 ing brackets on said walls.

5. A broiler drawer, comprising a frame, end walls, one at least of said end walls being pivotally supported on said frame, the pivotal support being located below the center of gravity 25 of said wall and closer to the opposite end wall than the plane of the pivotally supported wall itself, and pan supporting brackets on said walls.

6. A broiler drawer, comprising a frame, a fixed end wall, an opposite end wall pivotally supported on said frame to assume under its own weight a position slanting away from said fixed end wall, and means for limiting the tilting movement of said pivotally supported wall in a direction away from the fixed wall.

7. A broiler drawer, comprising a frame, a fixed wall supported thereby and an opposite wall pivotally supported on said frame in such manner as to normally assume a position slanting away from the fixed wall, means for limiting the movement of said pivotal wall away from the fixed wall, and means for limiting the movement of said pivotal wall in direction towards the fixed wall.

8. A broiler drawer, comprising a frame having longitudinal bars and a transverse bar, an end wall fixedly supported on the frame in opposition to said transverse bar, an end wall pivotally supported on said frame, the pivotal support for said end wall being below the center of gravity and being closer to the fixed end wall than the plane of said pivotally supported wall, the transverse bar of the frame having portions adapted to stop the pivotal movement of said second named wall in a direction away from the fixed wall, and also having portions adapted to stop the movement of said pivotal wall in a direction towards said fixed wall, and pan supporting brackets on each of said walls.
